UNITED STATES PATENT OFFICE.

WILLIAM LOUIS BUSH, OF WATERTOWN, NEW YORK, ASSIGNOR OF
ONE-HALF TO THE WATERTOWN SPRING WAGON COMPANY, OF SAME
PLACE.

COMBINED AXLE AND SPRING CLIP.

SPECIFICATION forming part of Letters Patent No. 424,092, dated March 25, 1890.

Application filed February 11, 1888. Serial No. 263,745. (No model.)

To all whom it may concern:

Be it known that I, WILLIAM LOUIS BUSH, a citizen of the United States, residing at Watertown, in the county of Jefferson and State of New York, have invented certain new and useful Improvements in a Combined Spring-Connection, Axle-Clip, and Pole or Shaft Coupling; and I do declare the following to be a full, clear, and exact description of the invention, such as will enable others skilled in the art to which it appertains to make and use the same, reference being had to the accompanying drawings, and to the letters of reference marked thereon, which form a part of this specification.

This invention relates to certain new and useful improvements in clips for carriages; and it consists of a certain novel arrangement and combination of parts, as will hereinafter more fully appear in the specification, and be pointed out in the claim.

The object of the invention is to construct a clip which shall be especially adapted for use in connection with "spring-vehicles," such as is more particularly described in a patent granted to John W. Whittle, September 22, 1885, No. 326,823.

In the accompanying drawings, forming a part of this specification, and on which similar letters of reference indicate the same or corresponding features, Figure 1 is a side elevation of one of the axles, showing the spring-support connected thereto and giving a front view of the clip proper. Fig. 2 is a transverse 35 sectional view taken on the line xx of Fig. 1, and showing the rear end of one of the shafts attached to the clip.

The letter A designates the axle, having its main portion deflected downwardly in a plane somewhat below the spindles proper and having an offset B at each end in substantially the same plane with the spindles themselves, and from which offsets the spindles proper extend.

45 I secure to the top or upper surface of the offsets B by screw-threaded extensions C and nuts D the clip and spring-support, the same consisting of a bar extending some distance

longitudinally with the offsets and terminating at its inner end in an eye to which the 50 spring-coupling G is attached, the spring itself H being attached to this latter coupling. The spring-support, as already observed, is securely fastened by the screw-threaded extensions, the forward end of which, or that 55 end which faces the animal drawing the vehicle, consists at its upper portion of a somewhat broadened plate I, which extends down a short distance and out from which in a longitudinal plane project the walls J of the 60 clip proper. The under surface of the plate I terminates in the same plane with the walls of the clip, and from this point it is comparatively small and screw-threaded to form the bolt C. The walls J of the clip are of course 65 provided with apertures in which fits the rear end L of the shafts, said end being secured by a bolt or otherwise, as may be desired.

It will be observed that I construct my clip and spring-support of one piece, thereby preventing any looseness or jarring of parts which might otherwise occur, and also at the same time cheapening the cost of manufacture of the article and rendering it stronger and lighter.

Having thus fully described my invention, what I claim as new, and desire to secure by Letters Patent, is—

In a device of the character herein described, the combination, with the axle having a depressed central portion and provided with offsets at its ends, of a spring H, spring-coupling G, spring-support mounted on said offsets and consisting of a bar having an eye at its inner end through which said spring-coupling is secured to it, a clip formed integral with the said support, an inverted-V-shaped piece having screw-threaded extremities C, and nuts D, all substantially as shown and described.

90 In testimony whereof I affix my signature in presence of two witnesses.

WILLIAM LOUIS BUSH.

Witnesses:

C. D. SHIRLEY,
FRANK YOUNGS.
